DEODORIZER

Charles H. MacFarland, Cleveland, Ohio, assignor
to The Scott & Fetzer Company, Cleveland,
Ohio, a corporation of Ohio

Application August 30, 1949, Serial No. 113,138

6 Claims. (Cl. 21—127)

1

This invention relates to an air conditioner for vacuum cleaners and more particularly to a device for supplying a vapor disinfectant and/or deodorizer to air within a portion of the cleaner through which the air passes during operation of the cleaner.

The invention has for an object to provide a device which supplies an air conditioning vapor to the interior of the dust collecting chamber of the cleaner so that the air passing through the said chamber is conditioned during operation of the sweeper and so that contamination of the air by dirt collected in the chamber is prevented during intervals between operations of the cleaner.

The invention has for a further object to provide an air conditioning device of simple and inexpensive construction that can be quickly and easily recharged at any time without removing it from the cleaner.

With the above and other objects in view, the invention may be said to comprise the air conditioning device as illustrated in the accompanying drawings hereinafter described, together with such variations and modifications thereof as will be apparent to one skilled in the art to which the invention pertains.

Reference may be had to the accompanying drawings forming a part of this specification in which;

Figure 1 is a side elevation of a vacuum cleaner to which the device of the present invention is applied, a portion of the dirt collecting chamber being broken away to show the air conditioning device;

Fig. 2 is a fragmentary vertical section on an enlarged scale taken on the line indicated at 2—2 in Fig. 1;

Fig. 3 is a fragmentary vertical section taken on the line indicated at 3—3 in Fig. 2;

Fig. 4 is a sectional view taken on the same line as Figure 3 with the absorbent pad and the pad retaining plate removed;

Fig. 5 is a horizontal section taken on the line indicated at 5—5 in Fig. 2 looking upward;

Fig. 6 is a perspective view of the retainer plate; and

Fig. 7 is a perspective view of the absorbent pad.

In the accompanying drawings the invention is shown applied to a vacuum cleaner of a well known type in which the cleaner is supported upon wheels 1 and comprises a suction nozzle 2, a fan casing 3 having an outlet 4, a dirt collecting chamber 5 to which the outlet 4 delivers,

2

a detachable dirt receptacle 6 which forms the bottom of the collecting chamber 5 and a filter bag 7 through which the air is discharged after passing through the dirt collecting chamber.

5 The chamber 5 has an upright end wall 8 provided with a central lug 9 on its inner face. The lug 9 is integral with the wall 8 and has a downwardly facing shoulder 10. The wall 8 is provided with a passage 11 that opens to the shoulder 10 through which liquid may be introduced to the interior of the chamber, the upper end of the passage 11 which opens to the exterior of the chamber being closed by detachable screw plug 12. The chamber 5 has side walls 13 disposed substantially at right angles to the end wall 8 and each of the walls 13 has a vertical rib 14 at a short distance from the wall 8. A retaining plate 15 is retained between the ribs 14 and the wall 8, the plate 15 having a supporting flange 16 at its lower end which has an upturned edge portion 17 that is adapted to bear against the interior of the wall 8. The plate 15 is adapted to be slid upwardly into the space between the ribs 14 and the end wall 8 of the chamber when 10 the receptacle 6 is detached and when in place within the chamber the end edges of the plate 15 engage the outer faces of the ribs 14 and the central portion of the plate adjacent its upper edge engages the interior of the lug 9. The plate 15 is positioned in the chamber 5 by engagement of its flange 16 with the lower ends of the ribs 14 and by engagement of its upper edge with lugs 18 integral with the wall 8.

A substantially flat pad 19 of absorbent material is held against the end wall 8 of the dust collecting chamber by the retaining plate 15, the bottom edge of the pad resting on the flange 16 and the upper edge of the pad being positioned immediately below the shoulder 10 so that liquid introduced through the passage 11 flows into the absorbent pad and is distributed to all parts of the pad. The wall 8 of the container is preferably bowed outwardly slightly intermediate the ends thereof so that a somewhat wider space is 20 provided between the retaining plate 15 and the wall adjacent the center of the wall and the pad 19 is of a thickness such that it is compressed between the end portions of the plate 15 and the wall 8 so that the pad and retainer plate are securely held in place by friction. The retainer plate 15 is a perforated plate having openings 20 distributed substantially throughout the height and width of the pad so as to expose a portion of the inner face of the pad to the air within the 25 dirt receptacle. The pad is charged with a vola-

tile liquid disinfectant and/or deodorant that is introduced through the passage 11. Sufficient liquid is preferably maintained in the pad to condition the air within the dirt collecting chamber during periods when the cleaner is idle as well as when the cleaner is in operation. During operation of the cleaner a large volume of air will be delivered by the fan into the dirt collecting chamber and discharged through the filter bag connected to the top of the collecting chamber, and the evaporation of liquid from the absorbent pad is at a relatively high rate so as to effectively disinfect and/or deodorize the air passing through the dirt collecting chamber and filter. By reason of the fact that the disinfectant and/or deodorant is delivered into the dust carrying air stream, the dust deposited in the collection chamber will have been subjected to the action of the conditioning material so that there is less danger of noxious fumes being released when the dirt receptacle is emptied. Also, the dust collecting chamber is in communication with the outer air through the suction nozzle and fan chamber during periods when the cleaner is not in use and the volatile air conditioning liquid in the pad 19 serves to condition the air within the chamber 5 during periods when the cleaner is not in use so as to prevent the issuance of disagreeable odors or contaminated air from the chamber to the surrounding atmosphere.

It is to be understood that in accordance with the provisions of the patent statutes variations and modifications of the specific devices herein shown and described may be made without departing from the spirit of the invention.

What I claim is:

1. In a vacuum cleaner a dust collecting chamber provided with an inlet for dust-laden air and an air outlet and having a wall provided with a passage opening to the chamber through which liquid may be introduced into the chamber intermediate the inlet and outlet, a pad of absorbent material within said chamber and having a portion of its surface exposed to the air within said chamber and a retainer for holding said pad against said wall in position to cover the passage opening and receive liquid delivered through said passage.

2. In a vacuum cleaner a dust collecting chamber provided with an inlet for dust-laden air and an air outlet and having an upright wall provided with a downwardly facing internal shoulder and with a passage through which liquid may be introduced that opens to the interior of the chamber through said shoulder, and a pad of absorbent material secured to said wall and having a portion positioned beneath said shoulder to receive liquid introduced through said passage.

3. In a vacuum cleaner a dust collecting chamber provided with an inlet for dust-laden air and an air outlet and having an upright wall provided with a downwardly facing internal shoulder and with a passage through which liquid

may be introduced that opens to the interior of the chamber through said shoulder, and a substantially flat pad of absorbent material secured against the interior of said wall with its top edge beneath and adjacent said shoulder to receive liquid introduced through said passage.

4. In a vacuum cleaner a dust collecting chamber having an upright wall provided with a downwardly facing internal shoulder and with a passage through which liquid may be introduced that opens to the interior of the chamber through said shoulder, a pad of absorbent material positioned against said wall and beneath said shoulder to receive liquid introduced through said passage, and a retainer for said pad comprising a plate engaging the inner face of the pad and having openings exposing portions of the inner face of the pad to the air within said chamber.

5. In a vacuum cleaner a dust collecting chamber having upright side walls and an upright end wall provided with an interior centrally disposed lug having a downwardly facing shoulder, said end wall having a passage for liquid opening to the interior of the chamber through said shoulder, each side wall having an upright rib near said end wall, a perforated retaining plate having opposite edge portions disposed between said ribs and said end wall, and a pad of absorbent material held between said retaining plate and said end wall, said pad being disposed beneath said shoulder to receive liquid introduced through said passage.

6. In a vacuum cleaner a dust collecting chamber having upright side walls and an upright end wall provided with an interior centrally disposed lug having a downwardly facing shoulder, said end wall having a passage for liquid opening to the interior of said chamber through said shoulder, each side wall having an upright rib near said end wall, a perforated retaining plate having opposite edge portions disposed between said ribs and end wall and a supporting flange along its bottom edge that projects toward said end wall, and a pad of absorbent material extending substantially the full width of said end wall and clamped between said retaining plate and said end wall, said pad having its bottom edge resting on said flange and its top edge beneath said shoulder to receive liquid introduced through said passage.
